UNITED STATES PATENT OFFICE.

CLARENCE G. CASHMAN, OF WAYNESBORO, PENNSYLVANIA, ASSIGNOR OF ONE-HALF
TO JOHN B. EADER, OF WAYNESBORO, PENNSYLVANIA.

VISE.

1,344,862.

Specification of Letters Patent. Patented June 29, 1920.

Application filed July 30, 1919. Serial No. 314,225.

To all whom it may concern:

Be it known that I, CLARENCE G. CASHMAN, a citizen of the United States, residing at Waynesboro, in the county of Franklin 5 and State of Pennsylvania, have invented certain new and useful Improvements in Vises, of which the following is a specification.

This invention relates to quick acting 10 vises and has for its object to provide in a vise improved means for rapidity in connecting the operating mechanism with the moving jaw, and also improved means for operating the moving jaw at a throw of the 15 lever, in either direction.

With these and other objects in view the device comprises certain novel constructions, combinations and arrangements of parts as will be hereinafter more fully described and claimed.

Referring to the accompanying drawings which are made a part hereof, and on which similar reference characters indicate similar parts,

25 Figure 1 is a view of the improved vise in side elevation,

Fig. 2 is a view of the improved vise in top plan,

Fig. 3 is a horizontal longitudinal sectional view taken on line 3—3 of Fig. 1,

30 Fig. 4 is a view of the sliding jaw in side elevation, removed from the housing structure,

Fig. 5 is a view of the clutch member in 35 side elevation,

Fig. 6 is a longitudinal sectional view of the clutch member taken on line 6—6 of Fig. 5,

Fig. 7 is a view of the clutch-actuating 40 spring shown in side elevation,

Fig. 8 is a view of the clutch-actuating spring shown in edge elevation,

Fig. 9 is a view in elevation of the shaft carrying the cams, and to which the lever 45 is connected,

Fig. 10 is a transverse sectional view through the shaft and cam, taken on line 10—10 of Fig. 9.

The improved vise which forms the subject matter of this application comprises a base 15 of substantially the usual and ordinary type adapted to be secured to a bench or other fixed object in the usual manner by inserting bolts through the ears 16. Upon 50 this base 15 a disk 17 is mounted for limited

rotary movement to change the angular position of the work operated upon by the vise, no novelty, however, residing in this adjustment, it being old in this class of implements.

Upon the disk 17 a housing 18 is erected providing space for the passage therethrough of the beam 19 of the movable jaw 20. Upon each side the beam 19 has countersunk therein a rack plate 21 and through 65 the beam and the rack plates 21 a slot 22 is provided for the purpose hereinafter described.

Within the housing 18 clutch members 23 are located having teeth 24 positioned and proportioned to engage the teeth of the rack bar 21. The end of the clutch member adjacent the teeth 24 is drilled to receive a spring 25 and a slot 26 is provided to receive the inclined or cam extremity 27 of the 70 spring 28, such cam extremity bearing against the spring 25 so that there is double spring action provided by the springs 25 and the springs 28. Preferably, though, not necessarily, these clutch members 23 with 75 their accompanying springs 25 and 28 are located upon opposite sides of the beam 19. Such use of two clutch members insures equality of action and avoids binding of the parts. The ends of the clutch members 23 80 opposite the teeth 24 bear against cams 29 formed integral with the shaft 30 which at its extremities is provided with multi-angular portions 31 to receive a lever 32 which may be placed upon either end of the shaft 90 30 as occasion may make desirable. The slot 22 in the beam 19 is properly proportioned to permit the passage therethrough of the shaft 30 so that in assembling the device the clutch members may first be inserted in the housing and the beam 19 inserted through the housing by means of the hand hold 33 and the shaft inserted transversely through its bearings and through the slot 22 of the beam. The clutch members 100 23 are now permitted under the action of their springs 25 and 28 to move slidably against the cams 29 and by reason of the shoulders adjacent such cams, prevent the removal of the shaft 30 until the contact between the clutch members 23 and the cams is again released.

After assembling the device, as just hereinbefore described, the operation is as follows. The lever 32 is raised to a vertical 110

position, as shown in full lines at Fig. 1, whereby the shaft 30 is rotated so that the major axes of the cams 29 also stand vertical. In this position the springs 25 and 28 force the clutch members 23 outwardly away from the rack 21 permitting the free movement of the jaw 20 and beam 19. This is accomplished by manipulating the jaw through engagement with the hand hold 33 closing the movable jaw into engagement with the work. The movement of the lever 32 in either direction to or toward the dotted line position shown at Fig. 1 first rotates the shaft 30 and the cams 29 forcing the clutch members 23 in a direction away from the axis of the shaft 30. By reason of the inclined slot 26 the cam extremity 27 and curvature of the spring 28, the movement of the clutch member 23 is translated into a transverse movement toward and into engagement with the teeth of the rack 21. The continued movement of the lever forces the clutch members a still farther distance in position to the spring 28, but being now in locked engagement with the beam 19, moves the beam 19 and movable jaw therewith. By reason of the formation of the cams 29 the device will remain in any position to which the lever 32 has been moved, retaining the work securely clamped between the jaws until the lever is returned to vertical whereupon the parts being again disconnected by the action of the springs 25 and 28 the work is released by the manual movement of the sliding jaw. This completes a cycle of operation and the device is in condition for repeating on any kind or size of work.

Having thus fully described my said invention, what I claim as new and desire to secure by Letters Patent, is:

1. In a vise, a housing, a jaw beam having spaced teeth along its side inserted through the housing, a clutch member positioned within the housing and having teeth proportioned to coact with the teeth of the beam, means to hold the clutch member normally and yieldingly with the teeth out of engagement, a cam adapted when oscillated in either direction to move the clutch into engagement with the teeth of the beam and to further move the beam after such engagement, and means to apply power to the cam.

2. A vise comprising a housing, a jaw beam freely movable within the housing, a rack formed upon the side of the jaw beam, a clutch member disposed within the housing and having teeth proportioned to interengage with the teeth of the rack, a spring tending to move the clutch out of engagement with the rack, a cam adapted when oscillated in either direction to move the clutch against the tension of spring into engagement with the rack and to provide for a further movement of the engaged beam, and means to apply power to the cam.

3. In a vise a housing appropriately mounted, a jaw beam freely slidable within the housing, a rack upon the side of the beam, a clutch member disposed within the housing and provided with teeth proportioned to interengage with the teeth of the rack, a spring tending to hold the clutch normally out of engagement with the rack, a shaft inserted through the housing and an appropriate opening in the beam, a cam carried by the shaft adapted to move the clutch into engagement with the rack and to provide for a further movement of the engaged beam, and means to apply power to the shaft.

4. A vise embodying a housing, a jaw beam freely slidable within the housing, a rack carried by the jaw beam, a clutch block located within the housing and adjacent the beam and provided with teeth to interengage with the teeth of the rack, a curved member secured to the exterior of the housing and having its extremity curved into the housing adjacent the rack, a cam extremity carried upon the curved member, a spring carried by the clutch block in yielding engagement with the cam extremity, a shaft journaled in the housing and inserted through an appropriate slot in the beam, a cam carried by the shaft in engagement with the clutch block adapted to move the clutch slidably upon the cam extremity of the curved member into engagement with the rack and providing for a further movement of the engaged clutch in opposition to the tension of the curved member, and means to apply power to the shaft.

5. A vise embodying a housing, a jaw beam freely slidable within the housing, a rack upon one side of the beam, a clutch block disposed within the housing and provided with teeth proportioned to interengage with the rack, a spring secured to the exterior of the housing and having its end curved into the housing adjacent the rack and into engagement with the clutch block and tending to normally hold the clutch block with its teeth out of engagement with the rack, a shaft journaled in the housing and passing through an appropriate slot in the beam and provided with cam portions engaging the ends of the clutch blocks adapted to move the clutch blocks against the tension of the curved springs into engagement with the rack and to provide for a further movement of the engaged rack against the tension of the curved springs, and means to apply power to rotate the shaft.

6. A vise embodying a housing, a jaw beam freely slidable within the housing, a clutch member positioned within the housing and provided with means adapted to engage with the beam, means to hold the clutch normally out of engagement with the beam.

beam, a shaft inserted through the housing and an appropriate slot in the beam, and a double acting cam carried by the shaft adapted to move the clutch into engagement with the beam upon a rotary movement of the shaft in either direction.

7. A vise comprising a housing, a jaw beam freely slideable within the housing and provided with a rack, a clutch disposed within the housing and provided with teeth proportioned to interengage with the teeth of the rack, a spring tending to hold the clutch normally and yieldingly out of engagement with the rack, a shaft journaled within the housing and provided with a double cam adapted to move the clutch upon a rotary movement of the shaft in either direction, and means to apply power to the shaft.

20 8. A vise embodying a housing, a jaw beam freely slideable within the housing and provided upon opposite sides with sunken panels, rack members inserted within the sunken panels, and carrying teeth, the outer extremities of which are substantially flush with the surface of the beam, clutches disposed within the housing upon opposite sides of the beam and provided with teeth proportioned to interengage with the teeth of the rack, springs secured to the exterior of the housing and having their ends curved into the housing and engaging the clutches and tending to hold the clutches normally and yieldingly out of engagement with the racks, a shaft journaled in the housing and inserted through an appropriate slot in the beam and provided with reduced cam portions into which reductions the extremities of the clutches are forced by their springs 40 and into engagement with the cams preventing the displacement of the shaft, and means to apply power to the shaft to rotate

the shaft and cam to move the clutches against the tension of their springs into engagement with the racks of the beam and to provide a further movement of the engaged beam with the clutches.

9. A vise embodying a stationary jaw, a movable jaw, a lever, means to apply the lever to either side selectively, and means whereby oscillation of the lever in either direction when located in either position moves the movable jaw.

10. A vise embodying a stationary jaw, a movable jaw, a lever, means to apply the lever to either side selectively, and means whereby the oscillation of the lever moves the movable jaw.

11. A vise embodying a stationary jaw, a movable jaw, a cam, means whereby oscillation of the cam moves the movable jaw, a lever, and means carried by the cam for engaging the lever upon either side of the stationary jaw selectively.

12. A vise embodying a stationary jaw, a movable jaw, a cam, means whereby the oscillation of the cam in either direction moves the movable jaw, a lever, and means carried by the cam for engaging the lever on either side of the stationary jaw selectively.

13. A vise embodying a stationary jaw, a movable jaw, a shaft extending through the stationary jaw, a cam carried by the shaft adapted to move the movable jaw, a lever, and means for connecting the lever selectively with the opposite ends of the shaft.

In witness whereof, I have hereunto set my hand and seal at Waynesboro, Pennsylvania this 26th day of July, A. D. nineteen hundred and nineteen.

CLARENCE G. CASHMAN. [L. S.]
